UNITED STATES PATENT OFFICE.

DORSEY M. WIRTH, OF BUCYRUS, OHIO.

BELT BUCKLE.

Application filed August 21, 1923. Serial No. 658,481.

To all whom it may concern:

Be it known that I, DORSEY M. WIRTH, a citizen of the United States, residing at Bucyrus, in the county of Crawford and 5 State of Ohio, have invented certain new and useful Improvements in Belt Buckles, of which the following is a specification.

It is the primary object of this invention to substantially improve and simplify 10 over the type of belt buckles shown and described in my co-pending applications filed December 2, 1922 and July 17, 1923 and bearing Serial Numbers 604,457 and 652,024, respectively.

15 In carrying out this invention it is my purpose to provide a belt buckle wherein an elastic tensioning means is provided between the buckle and the end of the belt attached thereto for allowing the expansion 20 and contraction of the belt while in position upon the waist of the wearer for thereby preventing the usual necessity of the adjustment of the belt while in use.

With the above and other objects in view 25 as the nature of the invention is better understood, the same comprises the novel form, combination and arrangement of parts as shown in the accompanying drawing, set forth in the following detailed specification 30 and claimed.

In the drawing:—

Figure 1 is a side elevational view of one form of my invention the same being shown as carried by one end of a belt,

35 Figure 2 is a bottom plan view thereof, Figure 3 is a bottom plan view of a slightly modified form of belt buckle, and

40 Figure 4 is a bottom plan view of an attachment that may be employed in conjunction with the type of belt buckle shown in Figure 3.

Now having particular reference to the drawing, and first to Figures 1 and 2, 5 indicates a belt buckle of well known construction that includes the usual arcuate-shaped top plate 5 formed upon opposite sides with flanges 6 that are provided with alined inclined slots 7 through which project the pintles 8 upon the ends of a corrugated cross roller 9, the free end of the belt which is indicated by 10 adapted to pass between this roller and the under side of said arcuate-shaped portion 5 whereby a pull upon the belt will naturally draw the roller upwardly against the belt and conse-

quently firmly maintain the same connected to the buckle as is obvious.

My invention per se embodies the provision of a cross pin 11 that is secured between said flanges 6 rearwardly of the roller 9 and pivotally secured to this cross pin is a wire bail member 12 the free ends of the legs thereof being formed with eyes 13 for engagement upon said cross pin. Bridging the legs of the bail member 12 is a pin 14 60 the opposite ends thereof being eyed at 15 for the reception of said legs, this cross pin 14 adapted to be engaged by the looped portion 10' of the before-mentioned belt 10 the opposite sides of this looped portion being 70 notched as at 10" for permitting of the proper engagement of this looped portion with the buckle as more clearly shown in Figure 2.

Surrounding the bail 12 rearwardly of 75 the cross pin 14 is a helical spring 16 that serves as a means for forcing the cross pin 14 in a direction forwardly for consequently applying tension to the belt 10.

In view of the above it will at once be 80 apparent that I have provided a highly novel and simplified form of tensioning means for belt buckles and one that will answer all of the purposes above ascribed.

Now having particular reference to Figure 3, 5' indicates the belt buckle that is provided at its side edges with flanges 6' between which extends a cross pin 8' that carries a locking tongue 9' for the purpose of locking the belt to the buckle when this 90 tongue is swung to the position shown this construction being of a conventional design and therefore clearly obvious to those skilled in the art. Pivotally secured to this cross pin 8' at opposite ends thereof are the front 95 ends of pendant flanges 17 formed upon a plate 18 the front edge of this plate adapted to be engaged by rearwardly extending fingers 19 that are formed upon or otherwise suitably secured to said cross pin 8' 100 whereby when the belt is secured to the buckle in a manner hereinafter described and the same positioned around the waist of the wearer the liability of the locking tongue 9' from becoming displaced is substantially reduced this particular construction being clearly set forth in the last mentioned pending application set forth above.

In this instance the eyed ends 13' of the bail 12' are engaged through openings in 110

the rear ends of the above mentioned flanges 17 of the plate 18 and spanning the legs of this bail, rearwardly of the plate 18, is a cross pin 14' the opposite ends thereof 5 being eyed for this purpose and these eyed ends being designated 15'. Also surrounding this bail rearwardly of this cross pin 14' is a helical spring 16' that answers the same purpose as the spring 16 in the form 10 of the invention shown in Figures 1 and 2.

With particular reference to Figure 4 there is shown an attachment for a belt buckle of the type disclosed in Figure 3 and in this instance the plate 18' is also formed 15 with guide flanges 17' to which are secured at the rear ends thereof the hooked ends 20 of rearwardly directed pins 21 the opposite ends of these pins being joined by a cross member 22 and surrounding each of 20 the pins between this cross member and a cross pin 23 are expansion springs 24. The cross pin 23 is freely slideable upon said rearwardly directed pins 21 and is normally forced forwardly by the action of said 25 springs 24 it being obvious in this instance that the belt 10' is to be looped around said cross pin 23 in a manner similar to the belt shown in Figures 1 and 2 the opposite edges

of this looped portion being also notched for purposes previously set forth. 30

In view of the above description it will at once be apparent that I have provided several novel forms of belt buckles the nature of the same being such as to answer all of the purposes ascribed and even though 35 I have herein set forth the most practical embodiments of the invention with which I am at the present time familiar, it is nevertheless to be understood that other modifications may be had without departing from the spirit and scope of the appended claim. 40

Having thus described my invention, what I claim as new and desire to secure by Letters Patent is:—

A buckle structure comprising a body having means for engaging a strap, a bar disposed transversely of the body, a bail having its ends pivotally connected with the bar, a bar slidably mounted upon the end portions of the bail, and a spring coiled about the outer portion of the bail and having its ends bearing against the side of the bar which is slidably mounted upon the bail. 50

In testimony whereof I affix my signature.
DORSEY M. WIRTH.
